UNITED STATES PATENT OFFICE.

HARRY D. ILLICK, OF GALESBURG, MICHIGAN.

HOLDER FOR SOUND-REPRODUCING RECORDS.

1,009,523.

Specification of Letters Patent. Patented Nov. 21, 1911.

Application filed April 27, 1911. Serial No. 623,692.

To all whom it may concern:

Be it known that I, HARRY D. ILLICK, a citizen of the United States, residing at Galesburg, in the county of Kalamazoo and 5 State of Michigan, have invented certain new and useful Improvements in Holders for Sound-Reproducing Records, of which the following is a specification, reference being had therein to the accompanying drawing.

10 This invention relates to holders for records of sound reproducing instruments and the principal object of the same is to provide a case that can be placed in a cabinet or other receptacle and which is so constructed that a large number of records can be safely stored in a small space, and in which the records are so arranged that they can be used in a regular predetermined order.

20 A preferred and practical embodiment of the invention is shown in the accompanying drawing wherein:—

Figure 1 is a view in front elevation of the improved record holder. Fig. 2 is a transverse vertical sectional view taken on the line 2—2, Fig. 1. Fig. 3 is a fragmentary vertical sectional view taken on the line 3—3, Fig. 2. Fig. 4 is a fragmentary vertical sectional view showing the manner of attaching the guards to the shelves of the holder. Fig. 5 is a detail perspective view of one of the guards. Fig. 6 is a fragmentary perspective view of one of the shelves.

Referring to the accompanying drawings 35 by numerals it will be seen that the improved holder comprises a body 7 that is vertically disposed and is semicircular in shape. A plate 8 conforms to the contour of body 7 and is fitted in the upper end thereof and a 40 similar plate 9 is fitted within the bottom of said body. The bottom plate 9 has its upper surface provided with a plurality of regularly spaced parallel semicircular grooves 10, and the top plate has its under surface

45 similarly grooved. Semicircular shelves 11 are arranged in regularly spaced parallel relation within the body 7 and have their upper and lower surfaces provided with regularly spaced parallel semicircular slots 12. 50 The arrangement of shelves divides the holder into separate horizontal compartments, and each compartment is divided into a plurality of independent vertical compartments by means of the semicircular partitions 13 which are arranged in spaced parallel 55 surrounding relation and have their

upper and lower ends fitted in the grooves of the shelves and the top and bottom plates and extend through the grooves 12 of the shelves 11. The vertical compartments 60 formed by the partitions 13 have their open ends at the front of the body 7, so that access can be had to said compartments at each side of the body 7. Said compartments being in surrounding relation, it will 65 be clear that they vary in size, the outermost one being the largest and the central one the smallest.

Guards 14 are provided for preventing the records accidentally falling from one 70 end of said compartment, said guards being formed of a single length of material and shaped to provide concaved rests 15 for the records in the compartments and with pendant spurs 16 for engaging the ends of the 75 grooves in the bottoms of said compartments. The opposite ends of the vertical compartments carry removable pegs 17 or equivalent abutments.

The shelves 11 and the top and bottom 80 plates 8 and 9 are rigidly but removably held in the body 7 by the rods 18 that pass through said body and enter the shelves and plates.

The improved holder is especially adapted 85 for use in holding the record in regular order and it will be seen that when in use the records may be taken from one end of a record compartment and returned to the compartment through the opposite end so that 90 an unused record is always at one end and a used record at the other end.

The guards 14 are used at the ends of the record compartments from which the records are removed so that when records are being 95 placed in the compartments from the other ends, they will not fall from the compartments. The removable pegs 17 are used when the compartments are filled with records.

100 What I claim as my invention is:—

1. A holder for sound reproducing records comprising a semicircular body, top and bottom plates therefor, shelves in said body and forming a plurality of compartments, 105 semicircular partitions in each compartment and arranged in spaced parallel relation to provide independent record compartments, guards extending across one of the ends of said record compartments and provided with concaved seats for records, said guards being provided with penetrating 110

spurs for engaging the bottoms of said compartments, and removable abutment pegs in the other end of said compartments.

2. A holder for sound reproducing records comprising a semicircular body, shelves therein dividing the body into compartments, semicircular partitions in said compartments and arranged in spaced parallel relation to provide independent record compartments, guards for one of the ends of

said record compartments, and removable abutments for the other ends of said record compartments.

In testimony whereof I hereunto affix my signature in presence of two witnesses.

HARRY D. ILLICK.
